UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,183,214.

Specification of Letters Patent.

Patented May 16, 1916.

Application filed September 7, 1915. Serial No. 49,239.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to telephone 10 exchange systems, and more particularly to improved signaling arrangements for telephone systems.

The object of this invention is to provide means for enabling a calling station to cause 15 the repeated signaling of a called line in a telephone system in which called lines are automatically signaled upon the establishment of a connection.

According to the main feature of this invention by producing various circuit interruptions in a circuit extending from a calling line to a selector switch or other connection establishing means, either the repeated actuation of an automatic signaling 25 means (for instance, automatic ringing) or the operation of a disconnecting device may be caused. The operation of the disconnecting device, such as a restoring magnet or disconnect lamp, will result in the manually or automatically controlled restoration 30 of the selector switch.

Other new and useful features of this invention will appear from the following description and the appended claims.

35 The drawings represent the circuits of a well-known connector switch and so much of the arrangement of a telephone exchange system as is necessary for a clear understanding of the present invention.

40 Supposing that a calling subscriber's or incoming (a) line has been extended by manual or automatic means to a trunk 1, 2, it will be seen that a circuit is closed from grounded battery through the left-hand winding of a 45 line relay 3, conductor 2, substation of calling subscriber A, conductor 1, and right-hand winding of relay 3 to ground. Relay 3 becomes energized and closes a circuit for slow acting relay 4 from ground, through 50 its armature and front contact and winding of relay 4, to grounded battery. The calling subscriber proceeds now to send out impulses for controlling a connector switch 5

to select an outgoing line leading to a called substation B. The calling subscriber actuates, in accordance with the called subscriber's number, a calling device 6 provided at substation A, causing thereby the opening and closure of the incoming line circuit including relay 3, which is thus intermittently 60 deenergized and energized in accordance with the numerical designation of the called line. Relay 4 being slow acting does not become deenergized upon the interruptions produced in its circuit by the vibration of 65 the armature of relay 3, and therefore, upon each release of the armature of relay 3, a circuit is closed from ground, through the armature and back contact of relay 3, the armature and front contact of relay 4, the 70 winding of a primary magnet 8, and wiper 10 of a side switch associated with connector 5, to grounded battery. Under the control of magnet 8, wipers 11, 12 and 13 of connector 5 are stepped in a rotary direc- 75

Upon the first release of the armature of relay 3, a circuit was closed for slow acting relay 14, through the armature and front contact of relay 4, and relay 14, in the same 80 manner as relay 4, remained energized during the vibration of the armature of relay 3. Relay 14 closed also a circuit for escapement magnet 16 from ground through side-switch wiper 15, front contact and armature 85 of relay 14, and the winding of escapement magnet 16 to grounded battery. Escapement magnet 16 controls upon its deenergization, the stepping of the side switch wipers. After the calling subscriber sends 90 out the first series of impulses, the circuit of line relay 3 is interrupted at the calling substation for a sufficiently long period to allow the deenergization of slow-acting relay 4, which relay in turn opens the circuit of slow-acting relay 14. The deenergization of slow-acting relay 14 results in the opening of the circuit of escapement magnet 16, whereupon the wipers of the side switch are stepped into position 2. 100

The calling subscriber proceeds now to send out the second set of directive impulses, causing first the energization of slow-acting relays 4 and 14, and then the stepping of the connector wipers in a vertical direction under the control of a secondary magnet 11. 105

After the second series of impulses have been sent out, line relay 3 remains energized and opens at its back contact the circuit of slow-acting relay 14. If the called subscriber's line is idle, the test wiper 13 of connector 5 does not find ground on the test conductor, and therefore escapement magnet 16 becomes deenergized upon the opening of its circuit by slow-acting relay 14, and moves the side switch wipers into position 3. A circuit is now closed from grounded battery, through side-switch wiper 10, conductor 20, the winding of ringing relay 21, back contact and armature of relay 22, and interrupter 23 to ground. Relay 21 intermittently closes and opens its contacts, and connects ringing current from an alternative ringing current source 24, through front contact and armature of relay 21, side-switch wiper 25, connector brush 11, the called subscriber's line, connector brush 12, side-switch wiper 26, and the lower armature and front contact of relay 21, to ground. When the called subscriber at station B 26 moves his receiver from the switchhook, or as soon thereafter as relay 21 again deenergizes, if it happens to be energized at the time, *i. e.*, during a silent period of interrupter 23, a circuit is closed from ground, 30 through side-switch wiper 15, conductor 30, right-hand winding of relay 31, back contact and upper armature of relay 21, the called subscriber's loop, lower armature and back contact of relay 21, and left-hand winding of relay 31 to grounded battery. Relay 31 by attracting its armature, closes a circuit for a self-locking relay 22, which upon energization opens at its back contact the circuit of relay 21, and this relay being 35 permanently deenergized, cuts off the ringing current from the called subscriber's line. Relay 22 closes also a locking circuit for itself from grounded battery, through its winding, front contact and right-hand armature, and front contact and armature of relay 3. to ground. Relays 22 and 31 remain energized as long as the called subscriber is engaged in conversation, and relay 3 remains energized as long as the calling subscriber A keeps his circuit closed.

As soon as subscriber B restores his receiver to the switchhook, relay 31 becomes deenergized and opens the original energizing circuit of relay 22. Should the calling subscriber at substation A desire to resignal subscriber B, he will produce short interruptions in the circuit of line relay 3, for instance, by actuating his switchbook 27. Relay 3 upon each deenergization, opens the locking circuit of relay 22, which closes at its back contact and left-hand armature the circuit of relay 21, causing thereby the application of ringing current to the called subscriber's line B in the same manner as above described. During the vibration of

the armature of relay 3, relay 4 remains energized whereby the release of the connector is prevented.

If the called line is busy, the test wiper 13 connects a ground found on the test conductor to magnet 16. This magnet remains energized and the side switch wipers are not advanced to position 3, and the calling subscriber is informed, in the well-known manner by means of a tone applied to his line, that the calling subscriber's line is busy.

After the conversation is terminated the calling subscriber opens the circuit of relay 3 for a long period, for instance, by hanging up his receiver on the switchhook 27. Upon the constant deenergization of relay 3, relay 4 becomes reenergized and closes a circuit from ground, through the armatures and back contacts of relays 3 and 4, off-normal contact 36 of connector 5, and the winding of a release magnet 35 to grounded battery. Under the control of magnet 35, the connector and the associated side-switch are released to normal, in which position, upon the opening of contact 36, magnet 35 becomes deenergized.

What is claimed is:

1. In a telephone exchange system, incoming lines and outgoing lines, means for extending an incoming line to an outgoing line, automatic means for signaling over said outgoing lines, means for producing short and long circuit interruptions in said incoming lines, means operation in response to said short circuit interruptions for causing the repeated operation of said automatic means, and means operative in response to said long circuit interruptions for restoring said first mentioned means.

2. In a telephone exchange system, incoming lines and outgoing lines, a selector switch for extending an incoming line to an outgoing line, automatic means for applying interrupted signaling current to said outgoing lines, a relay associated with one end and a variably operable circuit interrupter with the other end of said incoming lines, means for causing the repeated operation of said automatic means, and means for restoring said selector, said last two mentioned means being controlled by said relay.

3. In a telephone exchange system, a plurality of substations, means for establishing a connection between a calling and a called substation, a full metallic circuit extending from the calling substation to said means, automatic means operative as a result of the establishment of the connection for signaling called substations, an interrupter for producing interruptions in said metallic circuit, and means responsive to said interruptions for causing the repeated operation of said automatic means.

4. In a telephone exchange system, a plurality of substations, means for establishing

- a connection between a calling and a called substation, a full metallic circuit extending from said calling substation to said means, automatic means for signaling called sub-
5 stations, an interrupter for producing interruptions of various duration in said metallic circuit, means responsive to interruptions of a certain duration for causing the repeated operation of said automatic means,
10 and means responsive to interruptions of a different duration for causing the restoration of said first mentioned means.
5. In a telephone exchange system, a plurality of substations, a selector switch for establishing a connection between a calling and called substation, a full metallic circuit extending from the calling substation to said selector, an interrupter for producing short and long interruptions in said metallic
15 circuit, automatic means for signaling called substations, a relay adapted upon actuation to disconnect said automatic means, releasing means for said selector, another relay controlling said releasing means, means responsive to said short interruptions for controlling said first mentioned relay and means responsive to said long interruptions for controlling said second mentioned relay.
6. In a telephone exchange system, incoming lines and outgoing lines, a selector for extending an incoming line to an outgoing line, automatic means for signaling selected outgoing lines, a self-locking relay controllable over a selected outgoing line for arresting the operation of said automatic means, a relay associated with said incoming line for controlling the locking circuit of said self-locking relay, a slow-acting relay controllable by said second mentioned relay,
30 releasing means for said selector switch operative upon the actuation of said slow-acting relay, a variable operable circuit interrupter associated with said incoming line, means operative upon a long interruption produced by said interrupter for actuating said slow-acting relay, and means operative in response to short circuit interruptions produced by said interrupter to open the locking circuit of said self-locking relay and
35 to prevent the operation of said slow-acting relay.
7. In a telephone exchange system, incoming lines and outgoing lines, means for extending an incoming line to an outgoing line, automatic means for signaling over said outgoing lines, means for producing short and long circuit interruptions in said incoming lines, means operative in response to short circuit interruptions for causing the
40 repeated operation of said automatic means,
- and a disconnecting device for said first mentioned means operative in response to said long circuit interruptions.
8. In a telephone exchange system, incoming lines and outgoing lines, a selector switch 65 for extending an incoming line to an outgoing line, automatic means for applying interrupted signaling current to said outgoing lines, a relay associated with said incoming line, means for causing the repeated 70 operation of said automatic means, and a disconnecting device for said first mentioned means, said means and device being controlled by said relay.
9. In a telephone exchange system, a plurality of lines, means for establishing a connection between a calling and a called line, a full metallic circuit extending from the calling line to said means, automatic means operative as a result of the establishment of 80 the connection for signaling called lines, a switch for producing interruptions in said metallic circuit, and means responsive to said interruptions for causing the repeated operation of said automatic means. 85
10. In a telephone exchange system, a plurality of lines, means for establishing a connection between a calling and a called line, a full metallic circuit extending between a calling line and said means, automatic means 90 for signaling said called line, a switch for producing interruptions of various duration in said metallic circuit, means responsive to interruptions of a certain duration for causing the operation of said automatic means, and a disconnecting device for said first mentioned means responsive to interruptions of a different duration.
11. In a telephone exchange system, a plurality of lines, means for establishing a connection between a calling and a called line, automatic means operative as a result of the establishment of the connection for signaling called lines, a switch for producing interruptions in said calling line, and means 100 responsive to said interruptions for causing the resignaling of called lines.
12. In a telephone exchange system, a plurality of lines, automatic means for establishing a connection between a calling and a called line, automatic means operative as a result of the establishment of the connection for ringing called lines, a switch for producing interruptions in said calling line, and means responsive to said interruptions for reringing called lines. 110
115
- In witness whereof, I hereunto subscribe my name this 3rd day of September A. D., 1915.

ALBEN E. LUNDELL.
